United States Patent Office.

STEPHEN V. BARNES, OF TRIANGLE, NEW YORK.

Letters Patent No. 93,269, dated August 3, 1869.

IMPROVED HOP-POLE SHARPENER.

The Schedule referred to in these Letters Patent and making part of the same.

To all whom it may concern:

Be it known that I, STEPHEN V. BARNES, of Triangle, in the county of Broome, in the State of New York, have invented a new and useful machine, which I call the "Revolving Hop-Pole Sharpener;" and I do hereby declare that the following is a full, clear, and exact description of the construction and operation of the same, reference being had to the accompanying drawings, and to the letters of reference marked thereon, making a part of this specification.

My machine is for the purpose of sharpening hop-poles, stakes, and posts, consisting of a conical cylinder, with a slot in the side to receive the cutter. The cylinder is fastened to an arbor that moves it, which arbor is also furnished with belt-pulley, balance-wheel, and buzz-saw. This combination, resting upon a suitable frame, is run by any motor equal in power to a one-horse endless-chain power, to which a belt may be attached.

I construct my hop-pole sharpener in the following manner, viz., I cast a conical iron cylinder, *g*, with an opening in the side to receive the knife-blade *b*, fastened to a wrought-iron arbor, bolted to cylinder *g*, containing the set-screws *i i*, moving in slots of the blade *b*, rendering it adjustable. The knife *b*, I curve on the edge one-half inch, sharpen the poles to a point, and bevel them back about eighteen inches. I make the cylinder proportionately large for stakes and posts.

The cylinder *g* is connected at its closed end to a common wrought-iron arbor, *h*, by face-plates *c c*, on

the end of each, bolted securely together. The open end is steadied by a boxing, *n*, fitted nicely to it.

The arbor *h* is also furnished with a belt-pulley, *j*, over which runs the belt that drives the "sharpener," with a buzz-saw, *d*, used for cutting off old poles, stakes, and posts, and for squaring the ends of new ones, with a balance-wheel *e* to regulate the motion, the whole of which running-part rests on a wooden frame, *o*, and works in metallic boxes, *k k*, situated near the extremities of the arbor *h*.

The pole, stake, or post is held to its place on the sliding frame *m* by a lever-clamp, *a*, which is worked by hand, (I think it more practicable to work it by hand, as it has to be changed so often.) The pole, stake, or post is moved into and out of the sharpener by the person who lays it on the frame *m*, sliding on the rods *ll*, steadies it during the process, and lays it away when sharpened.

Having described my improvement,

What I claim as new, and desire to secure by Letters Patent, is—

The arrangement, upon a suitable frame, of the hollow conc-shaped cylinder *g*, and its interior projecting blade *b*, saw *d*, sliding grooved frame and lever *a*, all the parts being constructed as described.

STEPHEN V. BARNES.
